CLAIM

The ornamental design for a flexible pouch, as shown and described.

DESCRIPTION

FIG. 1 is a front elevational view of the flexible pouch;
FIG. 2 is a right side elevational view of the flexible pouch;
FIG. 3 is a top plan view of the flexible pouch;
FIG. 4 is a back elevational view of the flexible pouch;
FIG. 5 is a left side elevational view of the flexible pouch;
FIG. 6 is a bottom plan view of the flexible pouch; and,
FIG. 7 is a perspective view of the flexible pouch.
